ROPE

Edward Horace White, Warrington, England, assignor to The Whitecross Company Limited, Warrington, England

Application September 27, 1943, Serial No. 503,998
In Great Britain September 18, 1942

1 Claim. (Cl. 57—145)

This invention relates to the manufacture of ropes and the like, and more especially to the construction of the locked coil wire ropes such as used for colliery winding gear, sinking, or other ropes built on the concentric or multiple strand pattern, more particularly of the non-rotating type. More particularly it relates to the method and apparatus of Patent No. 1,992,707, according to which the tendency of the core to untwist is increased by putting extra turns into it by rotation whilst the outer wires or the like are laid around it whilst avoiding untwisting of the outer covering layer of the wires or the like after they have been laid upon the core. According to that patent also, the extra turns or twists may be given to the core while it is in the process of having the final outer covering of locked coil wires or the like placed upon it whilst avoiding untwisting of the outer covering layer of the wires or the like after they have been laid upon the core.

In winding, and other ropes, made by the process referred to, successful results have been obtained in all cases, but in connection with the largest diameter of winding ropes made of locked coil construction, it is found that if the users do not re-set the ropes carefully to allow the self-tightening properties to operate in a manner which would take up the stretch in the outer wires, the outer covering may become loose on the core, and unevenness develop in waves, due to the slipping of the outer covering wires on the core, and consequent local overcrowding.

The object of the present invention is to provide for the overcoming of this difficulty, in the case of non-twisting ropes, especially those according to United States Patent No. 1,992,707.

After much experiment it has been found that this can be effected by means of a supplementary layer in the outer covering of the rope, and that it is particularly applicable to the case of large ropes, that is to say, ropes from a diameter of one and five eighths or one and three quarter inches upwards, the extra layer being laid in a direction, that is to say to a hand, similar to that of the outer layer of the cover and opposite to the hand or lay of the layers of wires constituting the core. Several results arise from this modification of the method of making ropes, one of which is that the re-setting of the rope from the end at which the load is attached is only required at comparatively long intervals, for instance at each re-capping, which has by statute to take place at intervals of not more than six months, 55

the rope will automatically re-set itself if allowed to do so, and the stretch in the outer wires will be automatically taken up and the outer layers remain tight.

5 Another valuable property in the new improved construction is that wire ropes of either right or left hand outer layers can be used on a winding drum which is arranged either right or left hand, whereas with other forms of locked coil or contra-lock winding ropes, it is necessary for the rope to be designed with the outer layer either right or left hand to suit the particular lay-out, i. e. when looking towards the shaft from the opposite side of the drum, if the under-rope winds on, commencing at the right on the drum and coiling towards the left, a rope of right hand lay must be used—compare British Safety in Mines Research Board Paper, No. 41, Chapter XI, which reads: "In certain cases the rope should be right hand or left hand lay, according to the direction in which it coils on the drum; that is, when looking towards the shaft, from the opposite side of the drum, if the under rope winds on commencing on the right and coiling towards the left, a rope with a right hand lay should be used. This will give the rope a tendency to tighten up during use; if a left hand lay is used the tendency will be to untwist."

30 The outer covering of ropes according to the present invention may be taken as comprising two layers, namely, the outermost layer, and an additional or supplementary layer between the outermost layer and the core.

35 The outermost layer should be of full-lock construction, but the supplementary layer which is laid to the same hand as the outer layer may be of full-lock, half-lock or segmental sections, or even a simple circular section.

40 This double outer layer of section wires is not simply a duplication from the aspect of using two layers instead of one, but it has a functional effect:

45 Firstly, from the fact that two layers in a concentric cable laid up in the same direction have a much greater area of contact than in the case of crossed layers, and therefore the outer layer is not inclined to slide upon the inner layer. This is illustrated in a diagram referred to below, 50 and is borne out in practice by the fact that the outermost layer has a strong gripping effect on the second layer, so much so that even when the usual end clamps or servings are removed there is very little tendency to slip or spring apart.

Secondly, with the two outer layers of wires

laid to the same hand, whether of sections or of rounds, a modification is required of the amount of overtight in the core, because the untwisting tendency of a double outer layer is, of course, greater than the untwisting tendency of a single outer layer; for which reason, in carrying out the modification or improvement referred to, it is advisable to use sections of smaller dimensions than in the case of only a single layer of outer covering wires. This point is elaborated below with reference to diagrams.

The invention consists in a non-twisting rope consisting of a core comprising a number of layers of wire wound to one hand, two layers of wires disposed around this core, these layers both being laid to the same hand but to the opposite hand from that of the core, and in which there is a twist in all the layers of the core with respect to the first or inner layer of the two covering layers, the sectional areas of the core layers multiplied by their respective distances from the centre being not less than the sectional area of the two outer layers multiplied by their respective distances from the central axis of the rope.

Referring to the accompanying diagrammatic drawings:

Figure 1 is an end elevation, and

Figure 2 a side elevation, with parts of the various layers removed, to illustrate one form of the present invention:

Figures 3 and 4 are views similar to Figures 1 and 2, but of a modified form of the present invention:

Figures 5 and 6 are diagrams to assist in explaining untwisting tendencies or resultant torque due to the load acting on the various layers of a rope.

Referring to Figures 1 and 2, the core consists of the parts of the rope marked *a*, comprising a number of layers of wires of circular or what may be termed of rail section, with voids or filled interstices indicated by *b*. The outermost layer indicated by *e* is formed of wires of full-lock section, laid to a hand opposite from that of the core. Between this outermost layer *e* and the core *a*, a supplementary cover layer *f* is disposed, wound to a hand opposite from that in which the core wires *a* and the outermost covering wires *e* are wound. The part broken away from Figure 2 from the wires of the outermost covering *e* shows, that there is a very large area of contact between the wires *e* and the wires *f*, which in practice results in a strong gripping effect, as referred to above.

In the form of the invention shown in Figures 3 and 4, the core wires *a* are similar to those in Figures 1 and 2, and the same applies to the wires *e* constituting the outermost layer of the cover. The supplementary layer of the cover is here formed by wires *g*, which are of circular section, but as in Figures 1 and 2, the wires *a* and *e* are wound to opposite hands, whereas the wires *e* and *g* are wound to the same hand. It is, however, preferred to use non-circular wires for the supplementary layer of the cover, in accordance with Figures 3 and 4, rather than wires of circular cross section, as illustrated in Figures 3 and 4, for circular cross section wires may tend to have a certain amount of cutting effect.

Wire ropes according to Figures 1 and 2 or 3 and 4 may conveniently be made by means of apparatus as described in United States Patent No. 1,992,707, or in either of British Specifications Nos. 388788 or 493077.

Referring now to Figures 5 and 6, a measure of untwisting tendency, or resultant torque due to the load acting on the various layers of the rope may be obtained from the sectional area of each layer multiplied by the distance of its centre-line from the central axis of the rope.

Referring to the diagram Figure 5 showing the outside of a concentric rope or strand, in which the wires are laid at an angle α to AC, the central axis, if it be imagined that one wire be taken and rolled off into a plane for the length of one complete lay, then in Figure 6 this is represented by CB, *W* representing the load acting along the central axis, *T* representing the tension in the wires due to this load at an angle of lay α .

The closing resultant of the triangle of force is represented by *AB* acting at right angles to the central axis.

From the simple triangle of forces, the torque= load multiplied by tangent of angle of lay (from diagram $AB=W \tan \alpha$) and this, divided over the layers of the rope according to their sectional area multiplied by the distance of the centre-line of each layer from the central axis of the rope, would enable the calculation to be made as to the relative balance between the two outer layers laid one hand, and the core layers laid to the other hand.

Assuming the sectional area of the various core layers, starting from the centre of the rope to be A_1, A_2, A_3 , and so on, acting at distances R_1, R_2, R_3 , and so on from the central axis of the rope, and the sectional area of the two outer layers to be $A_{O.1}$ and $A_{O.2}$ respectively, acting at distances of $R_{O.1}$ and $R_{O.2}$ from the central axis of the rope, then in general the design of rope should be such that whatever the sections used in the various layers, the torque resulting from the sectional areas of the core layers multiplied by their respective distances from the centre, should not be less than the torque resulting from the sectional area of the two outer layers multiplied by their respective distances from the central axis of the rope, i. e.,

$$(A_1 \times R_1) + (A_2 \times R_2) + (A_n \times R_n) > (A_{O.1} \times R_{O.1}) + (A_{O.2} \times R_{O.2}).$$

The over-balancing effect which keeps the outer layers tight will then be provided by the overtight put into the core, the amount of which is capable of calculation, and easily ascertained by trial, as is mentioned in the patent specification referred to above.

The computation just given assumes that the angle of lay is constant throughout and some small adjustment is required where a wide variation occurs between the angles of lay in different layers.

General

The present invention is best applied to those cases where the outer layer is of full-lock construction only, and to ropes of one and five eighths inches diameter and larger, in which the total sectional area of the wires of the two outer layers which is required for practical working conditions can be so designed that the untwisting moment of these two layers remains less than the untwisting moment of the core, plus overtight, that is, plus the additional untwisting moment due to the overtight which is put in to the core, whilst the supplementary layer to the opposite hand is laid around it. The overtight is put into the core whilst the supplementary layer

is being laid round it. The outermost layer of full-lock wires is then laid on.

In ropes of a smaller diameter than one and five eighths inches the sectional area of the wires of the outer layers may have to be so reduced in order to give effect to this requirement that they would not be heavy enough to provide the necessary wearing surface, and in any case the necessity for special treatment in the construction of ropes of less than one and five eighths inches diameter does not arise, to such an important degree.

A property observed in ropes made by the new modified construction is that a straight rope may be obtained, with no tendency to curl at any part of its length, whereas in new ropes of either the original contra-lock or other locked coil constructions, a set or curl can be observed when the rope is cut at any point, or released from tension after pulling off from its reel. This apparently means that the internal stresses in the complete structure under the modified construc-

tion are either absent, or more perfectly balanced than with the other constructions referred to, in which the set or curl indicates some unreleased stresses remaining, and in addition this property renders the ropes easier to handle through slightly greater flexibility and freedom from tendency to kink.

I claim:

10 A non-twisting rope consisting of a core comprising a number of layers of wire wound to one hand, two layers of wires disposed around this core, these layers both being laid to the same hand but to the opposite hand from that of the core, and in which there is a twist in all the 15 layers of the core with respect to the first or inner layer of the two covering layers, the sectional areas of the core layers multiplied by their respective distances from the centre being not less than the sectional area of the two outer 20 layers multiplied by their respective distances from the central axis of the rope.

EDWARD HORACE WHITE.
